ADJUSTABLE SCAFFOLD BASE

Thomas C. North, Zelienople, Pa., assignor to
Universal Fittings & Scaffolding Company,
Zelienople, Pa., a corporation of Pennsylvania

Application September 18, 1946, Serial No. 697,605

6 Claims. (Cl. 304—2)

1

This invention relates to scaffolds and, in particular, to a scaffold base or substructure for supporting prefabricated units of scaffolding.

In many cases the ground or foundation on which a scaffold rests is uneven and, in order to provide horizontal working platforms, the scaffold legs must be adjusted vertically to compensate for the unevenness. Such adjustments have been accomplished in various ways, such as by using telescoping legs or by adding short adapter lengths to the lower ends of the legs. In either case the scaffold may tend to be unsteady and to wobble if the legs are lengthened very much.

A major disadvantage of prior scaffolds arises when the ground slopes upwardly away from the wall along which the scaffold extends. The scaffold legs next to the wall can be lengthened or blocked up to level the scaffold, but that raises the lowest stage or working platform that much farther from the ground level at the wall. A workman standing on the ground then no longer may be able to work up to the first platform without standing on an improvised support. This is because the end panels of such scaffolds are of a height that just allows an average workman standing on a platform or surface even with the bottom of the panels to work conveniently up to the next platform, a distance generally of about four and a half or five feet.

It is among the objects of this invention to provide a scaffold substructure which makes vertical adjustment of the scaffold legs unnecessary, which is formed to support a working platform at any desired level above the ground, which has strong and rigid vertically adjustable legs, and which can be quickly and securely fastened to a scaffold mounted thereon.

In accordance with this invention a scaffold substructure is formed from a pair of spaced, parallel end frames connected together by braces that hold them upright to form a stable structure. Each of the frames includes a pair of spaced, parallel legs which are connected together below their upper ends by means of a horizontal cross member which is adapted to support the planks of a working platform. The cross members also are designed for supporting a scaffold. The cross members are connected to the legs by members, preferably collars, that are adjustable axially of the legs so that the cross members can be moved up and down on the legs, or the legs can be adjusted vertically relative to one another to compensate for uneven ground on which the substructure may rest.

The collar may be provided with transverse

2

openings adapted to register with different vertically spaced openings in the legs, and pins can be inserted in the registering openings to hold the collar in place. Most suitably, horizontal cross braces connect the cross members and inclined braces connect the legs. The ends of the inclined braces may be connected to the legs at any of the leg openings so that when a vertical adjustment of the legs is made, the position of the braces along the legs can be changed as desired.

The preferred embodiment of my invention is illustrated in the accompanying drawings of which Fig. 1 is an end view of the substructure showing a scaffold unit supported thereon; Fig. 2 a side view of the same assembly; Fig. 3 a plan view of the substructure; and Figs. 4 and 5 enlarged sections along lines IV—IV and V—V of Figs. 1 and 2, respectively.

Referring to the drawings, the substructure 1 comprises a pair of spaced, parallel end frames 2 and 3 each of which has a pair of vertical legs 4 and 5 connected together by a horizontal cross member 6. The legs preferably are formed from pipe, and the cross member from an angle bar which is adapted to support planking (not shown) on its upper surface in order to form a stage or working platform. Beneath the cross member the legs are connected by an inclined brace 7. Horizontal braces 8, Fig. 3, extend diagonally between the cross members of the end frames to maintain them parallel and to help keep them square. As best seen in Fig. 5, braces 8 are connected to the horizontal cross members by downwardly projecting pins 9 formed on the ends of the braces and fitting into vertical sleeves 10 welded to the inside of the cross members. The sleeves are positioned on the lower portions of the cross members so that when pins 9 are inserted therein the tops of braces 8 will lie in a plane at least as low as the upper surface of the cross members in order to avoid interfering with the working platform. The end frames also are connected together by inclined braces 11 attached to their legs. The substructure can be extended to any desired length by adding more end frames and the necessary braces.

The substructure, as stated, is designed for supporting a scaffold. One scaffold unit, shown 50 mounted on the substructure in Figs. 1 and 2, can be of any standard type known to this art. This unit is formed from spaced apart prefabricated end frames each having tubular legs 12 connected by suitable braces, and braces 13 connecting the end frames to form a rigid structure.

The lower ends or feet of scaffold legs 12 rest on cross members 6 of the substructure where they are prevented from moving laterally by means of plugs 14 welded to the tops of the cross members and projecting up into the lower ends of the tubular legs of the scaffold.

In order to more rigidly connect the lower unit of the scaffold to the substructure, and also to provide additional bracing for substructure legs 4 and 5, the upper ends of the substructure legs are extended above the connecting cross members a considerable distance, and means are provided for detachably connecting the upper ends of the legs to the adjacent sides of the scaffold end frames. Preferably, the connecting means consist of yoke-like clamps such as shown in Figs. 1 and 4. Each clamp is formed from a pair of spaced, parallel bars 16 rigidly connected by a cross-piece 17 between their ends. The outer ends of the bars straddle the upper end of one of the substructure legs and are pivotally connected to it by means of a horizontal pivot pin 18 so that the clamp can be swung outwardly to the dotted line position shown in Fig. 1 when not in use, or inwardly above the underlying cross member when a scaffold is supported on it. In use the bifurcated inner or free end of the clamp straddles the adjoining leg 12 of the scaffold and keeps it from tilting lengthwise of the substructure. The clamp is held in operative position by a retaining pin 19 extending through its inner end so that the scaffold leg also is held between this pin and cross-piece 17.

Another feature of this invention is that the legs of the substructures are adjustable in order to provide a horizontal working platform regardless of any unevenness in the ground or foundation upon which they rest, and also in order to provide a lower working platform at any desired level above the ground. Accordingly, the opposite ends of cross members 6 are provided with cylindrical collars 21 which encircle legs 4 and 5 on which the collars are slidable vertically. Each collar is provided with a pair of aligned radial openings adapted to register with any desired set of similar openings 22 extending through the substructure legs at vertically spaced intervals. Removable pins 23 extend through the registering openings to hold the collars in the selected positions. Vertical adjustments of the legs are made by sliding them up or down through the collars the distance necessary to compensate as much as possible for the unevenness of the ground. Any possible remaining unevenness may be taken care of by short filler blocks under one or more of the substructure feet, so that cross member 6 will remain horizontal. Also, since the legs of the substructure are made in one piece and are neither telescoped nor jointed, they remain rigid when extended below the cross members and thus contribute to the stability of the structure. It is unnecessary to adjust the length of the scaffold legs.

When the leg adjustments are made, the positions of inclined braces 7 and 11 along some or all of the legs can be changed to the extent necessary. The ends of the braces are connected to the legs by bolts 26 extending through leg openings 22. Thus, if leg 5, Fig. 1, should be raised in the encircling collar, it would be necessary to attach the lower end of brace 7 to the leg at a point closer to its lower end.

If all of the work is to take place as substantially the same level, a working platform can be located at a level most convenient for that work by removing pins 23 and then moving cross

members up or down the substructure legs to a position where the working platform under consideration will be located at the desired height.

One of the most important uses for this substructure is on ground that slopes upwardly away from the wall on which work is to be performed. In such cases heretofore it has been necessary to lengthen or block up the scaffold legs next to the wall to level the scaffold. This raised the lowest or first working platform to a greater height above the ground at the wall than would be the case if the ground were level. The objection to this is that the first platform then is so far above the ground that the average height 15 workman can not work from the ground up to it, and therefore must stand on boxes or other type of temporary elevated support to reach the platform. With the substructure disclosed herein, however, such an undesirable situation is 20 overcome, because instead of having to lengthen the substructure legs next to the wall, the length of the legs removed from the wall and on higher ground can be shortened by moving them upwardly through the adjoining collars 21. The desired 25 spacing between the lowest platform and the ground at the wall therefore can be maintained the same as the spacing between the platform and the next one above it. The same thing is 30 true when the ground slopes lengthwise of the wall. In such a case the desired spacing between the lowest platform and ground at the bottom of the incline can be maintained, and the rest of the substructure legs moved upwardly through their collars the amount necessary to keep the 35 platform level.

According to the provisions of the Patent Statutes, I have explained the principle, construction and mode of operation of the invention and have illustrated and described what now is 40 considered to be the best embodiment of the invention. However, it is understood that, within the scope of the appended claims, the invention may be practiced by other forms than those specifically illustrated and described.

45 I claim:

1. A scaffold substructure for use in supporting a scaffold formed of a pair of spaced parallel end frames each having a pair of spaced parallel legs, said substructure comprising a pair of spaced parallel end frames, and braces connecting said frames for holding them upright, each of said substructure frames including a pair of spaced parallel legs independently adjustable vertically relative to each other, a horizontal cross member between the substructure legs adapted to support a working platform, means adjustable axially of the said substructure legs for connecting the ends of said cross members thereto a material distance below the upper ends of the legs, the legs of each end frame of said scaffold resting on the cross member of each end frame of said substructure whereby said scaffold is supported, vertical plugs between said pair of said substructure legs projecting upwardly from each cross member and adapted to project into the legs of said scaffold, and clamping means pivotally connected to the upper end of each substructure leg and adapted to be swung into clamping engagement with an adjacent scaffold leg supported by said cross members.

2. A scaffold substructure for use in supporting a scaffold formed of a pair of spaced parallel end frames each having a pair of spaced parallel legs, said substructure comprising a pair of spaced parallel end frames, and braces connecting said

frames for holding them upright, each of said substructure frames including a pair of spaced parallel legs independently adjustable vertically relative to each other, a horizontal cross member between the substructure legs adapted to support a working platform, means adjustable axially of the said substructure legs for connecting the ends of said cross members thereto a material distance below the upper ends of the legs, the legs of each end frame of said scaffold resting on the cross member of each end frame of said substructure whereby said scaffold is supported, vertical plugs projecting upwardly from the ends of each cross member and adapted to project into the legs of said scaffold, a yoke straddling the upper end of each substructure leg, and means pivotally connecting the yoke to that leg to permit the free end of the yoke to be swung to a position above the underlying cross member, said free end of the yoke being bifurcated to adapt it to straddle an adjacent scaffold leg supported by said cross members.

3. A scaffold substructure for use in supporting a scaffold formed of a pair of spaced parallel end frames each having a pair of spaced parallel legs, said substructure comprising a pair of spaced parallel end frames, and braces connecting said frames for holding them upright, each of said substructure frames including a pair of spaced parallel legs independently adjustable vertically relative to each other, a horizontal cross member between the legs adapted to support a working platform, said cross members having a flat upper surface, collars secured to the opposite ends of each cross member and slidably receiving the legs, each of said legs being provided with vertically spaced openings, said collars being provided with transverse openings, means adapted to be inserted in said collar openings and any of said leg openings to lock the cross members on the substructure at different levels, the legs of each end frame of said scaffold resting on the cross member of each end frame of said substructure whereby said scaffold is supported, vertical plugs mounted on said flat surface of each cross member near its ends, said plugs projecting upwardly and being adapted to project into the legs of said scaffold resting on said flat surface, and clamping means pivotally connected to the upper end of said substructure legs and adapted to be swung into clamping engagement with an adjacent scaffold leg supported by said cross members.

4. A scaffold substructure for use in supporting a scaffold formed of a pair of spaced parallel end frames each having a pair of spaced parallel legs, said substructure comprising a pair of spaced parallel end frames, and braces connecting said frames for holding them upright, each of said substructure frames including a pair of spaced parallel legs independently adjustable vertically relative to each other, a horizontal cross member between the legs adapted to support a working platform, means adjustable axially of said substructure legs for connecting the adjacent ends of said cross members thereto, the legs of each end frame of said scaffold resting on the cross member of each end frame of said substructure whereby said scaffold is supported, means between said pair of legs projecting upwardly from each cross member and adapted to receive the feet of the scaffold and keep them from moving

laterally, clamping means connected to said frame and adapted to grip the legs of said scaffold and hold the scaffold on said cross members.

5. The combination of a scaffold and a scaffold substructure, said scaffold comprising a pair of spaced parallel end frames and braces connecting said frames for holding them upright, each of said end frames including a pair of spaced parallel legs and a cross member between the legs; and said substructure comprising a pair of spaced parallel end frames, and braces connecting said frames for holding them upright, each of said substructure end frames including a pair of spaced parallel legs independently adjustable vertically relative to each other, a horizontal cross member between the legs adapted to support a working platform, means adjustable axially of said legs for connecting the ends of said cross member thereto, the legs of each end frame of said scaffold resting on the cross member of each end frame of said substructure whereby said scaffold is supported, and means mounted on each of said substructure cross members for receiving said scaffold legs and keeping them from moving laterally.

6. The combination of a scaffold and a scaffold substructure, said scaffold comprising a pair of spaced parallel end frames and braces connecting said frames for holding them upright, each of said end frames including a pair of spaced parallel legs and a cross member between the legs; and said substructure comprising a pair of spaced parallel end frames, and braces connecting said frames for holding them upright, each of said substructure end frames including a pair of spaced parallel legs independently adjustable vertically relative to each other, a horizontal cross member between the legs adapted to support a working platform, means adjustable axially of said legs for connecting the ends of said cross members thereto a material distance below the upper ends of the legs, the legs of each end frame of said scaffold resting on the cross member of each end frame of said substructure whereby said scaffold is supported, means between said pair of legs projecting upwardly from said substructure cross members for receiving said scaffold legs and keeping them from moving laterally, and clamping means pivotally connected to the upper end portions of the substructure legs for gripping the scaffold legs and holding the scaffold on said substructure end frames.
